COTTON TAMPER

Lonnie E. Haynes, Birmingham, Ala.

Application July 16, 1937, Serial No. 154,062

1 Claim. (Cl. 100—25)

This invention relates to cotton tampers for compressing cotton into bales of a selected weight and has for the primary object the provision of a device of this character which will be rapid in 5 operation, simple in construction and may be successfully driven by a minimum amount of power and will produce a maximum amount of pressing power on the cotton to compress the latter into bale form.

Another object of this invention is the provision of means for automatically feeding cotton into position for tamping in accordance with the movements of the tamper.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a front elevation partly in section illustrating a cotton tamper constructed in accordance with my invention.

Figure 2 is a side elevation, partly in section, illustrating the same.

Figure 3 is a top plan view illustrating the device.

Figure 4 is a sectional view taken on the line 30 4—4 of Figure 3.

Figure 5 is a reversing rack bar.

Figure 6 is a sectional view taken on the line 35 6—6 of Figure 5.

Figure 7 is a sectional view taken on the line 7—7 of Figure 2.

Referring in detail to the drawings, the numeral 1 indicates a main frame of any desired construction on which is secured a shaft mounting 2 having vertical guides to slidably receive a stem 3 of a tamper 4, the latter being arranged for vertical reciprocation and adapted to be associated with a baling frame or similar device to tamp cotton therein, a part of which is shown at 2'. The stem 3 has secured thereto relatively 45 spaced pins 4' engaged by teeth of a gear 5. The rotation of the latter in opposite directions brings about reciprocation of the tamper 4. The tamper 4 includes a head 6 having yieldably secured thereto a face plate 7 adapted to engage with 50 the cotton for the purpose of packing the cotton in a baling frame or similar device 2'. The gear 5 is secured to a shaft 8 and the latter is journaled in the mounting 2 and has secured thereon a reversing rack bar 9' of annular formation and 55 provided with arcuately arranged and relatively

spaced pins 9 and also provided with a double shaft slot 10 of arcuate shape presenting a pair of runs for a shaft 11, the latter having secured thereto a pinion or gear 12 which meshes with pins 9. The shaft 11 is journaled in a frame 13 5 and the latter is hinged onto the mounting 2 by a power shaft 14, the latter also being journaled in the mounting 2 and having secured thereto a belt pulley 15 and a gear 16 which meshes with the gear 17 secured on the shaft 11. 10 The gear 17 is much larger than the gear 16 so that power delivered by the power shaft 14 will be increased to the shaft 11. The pins 9 are mounted in a wall 18 of the rack bar 9' and are also connected by an arcuate shaped spacer 19. 15 Continuous rotation is imparted to the shaft 11 from the drive shaft 14 and the gear 12 thereof meshing with the pins 9 brings about rotation of the rack bar 9' in opposite directions and the latter being secured on the shaft 8 rotates said 20 shaft in opposite directions and thereby brings about reciprocation of the tamper 4. A power source of any well known character and (not shown) is belted to the pulley 15. An idler pulley 16' is arranged adjacent the pulley 15 on 25 which the belt may be placed when not desiring operation of the tamper with the power source in operation.

The frame 13 is free to swing so that the shaft 11 may follow the runs of the slot 10 and pass 30 about the ends of the spacer 19 and in order that the swinging movement of the frame 13 may be limited an adjustable check 20 is connected thereto and on the main frame.

A hopper 36 is mounted on the main frame 1 35 adjacent to the path of movement of the tamper and its discharge end is controlled by a gate 37 of substantially triangular shape in cross section and pivotally mounted at its apex, as shown at 38. A lever 39 is pivoted on a bracket 40 carried by 40 the main frame and has one end pivotally connected to the gate 37 by a link 41. An arm 42 is fixed on the swinging frame 13 and a link 43 pivotally connects the arm to the lever 39. The gate 37 will thus be operated in a timed movement with the reciprocation of the tamper so that cotton may be discharged in the path of movement of the tamper when the latter is in its uppermost position and the hopper closed during 45 the downward movement of the tamper.

What is claimed is:

A tamping apparatus comprising a supporting structure, a tamping element mounted for reciprocation on said supporting structure and including a rack bar, a gear meshing with said rack 55

- bar, a shaft journaled on the supporting structure and having the gear secured thereto, an annular rack bar secured on said shaft and provided with a slot providing double runs, teeth 5 forming elements providing part of said annular rack bar and arranged in annular formation adjacent the slot and having the runs thereof positioned at opposite sides of the teeth, a frame pivoted on the supporting structure, a second 10 shaft journaled on said frame and extending into the slot of the annular rack, a gear secured to

the second named shaft and meshing with the teeth of the annular rack, a power shaft journaled on the supporting structure, gears connecting the power shaft with the second named shaft, a cotton hopper carried by the supporting structure, a gate for controlling said hopper, an operating means actuated by the pivoted frame and connected with said gate for opening and closing the same in accordance with the movement of the tamper element. 5

LONNIE E. HAYNES. 10
